(57) **CLAIM**

The ornamental design for a ring guard for utensil, as shown and described.

DESCRIPTION

FIG. 1 is a side, top, perspective view of the ring guard for utensil with a utensil (measuring spoon) portion thereof shown in phantom;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines are for illustrative purposes only and form no part of the claimed design.
